UNITED STATES PATENT OFFICE.

CHARLES E. SAVAGE, OF GROVETON, NEW HAMPSHIRE.

SULFUR-BURNER.

No. 841,576.

Specification of Letters Patent.

Patented Jan. 15, 1907.

Application filed October 24, 1906. Serial No. 340,286.

To all whom it may concern:

Be it known that I, CHARLES E. SAVAGE, a citizen of the United States of America, and a resident of Groveton, in the county of Coos 5 and State of New Hampshire, have invented certain new and useful improvements in Sulfur-Burners, of which the following is a specification.

Some kinds of sulfur—such, for instance, 10 as that which is mined in Louisiana and is known to the trade as "Louisiana sulfur"—contains an oily substance which comes out of the sulfur when it is melted, and this oil being lighter than the sulfur rises to the top 15 during combustion. This oil at the top of the sulfur prevents perfect combustion and is very objectionable for that reason.

To provide a device in which such sulfur may be readily burned is the object of the 20 present invention; and it consists, primarily, in a burner which is tilted or rocked over a fixed point, this tilting preferably being done automatically by means of a hydraulic mechanism. Preferably this hydraulic mechanism is provided with means whereby the burner will be stopped at the end of its movement in either direction and retained in this position for a time before it is moved in the opposite direction.

25 The invention consists, further, in a suitable seal between the movable or rocking oven-casing and the fixed outlet-pipe thereto.

It consists, further, in providing a plurality of oven-casings, the first of which is 30 controlled by a hydraulic device, while each succeeding oven-casing is controlled by the movement of the preceding oven-casing.

The invention consists, furthermore, in certain novel features of construction and 40 arrangement of parts, which will be readily understood by reference to the description of the drawings and to the claims hereinafter given.

45 Of the drawings, Figure 1 represents an elevation of a burner embodying the features of this invention shown in its lowest position, while its highest position is indicated in dotted lines. Fig. 2 represents a front elevation of a pair of burners adapted to operate in conjunction, certain of the parts being shown in section. Fig. 3 represents a plan view of the hydraulic devices for tilting the 50 oven-casings. Fig. 4 represents a central vertical section in the rear end of the burner, 55 showing the seal between said oven-casing and the fixed outlet-pipe; and Figs. 5 and 6

represent sections through the three-way valve by which water is admitted or exhausted from the hydraulic cylinders.

Similar characters designate like parts 60 throughout the several figures of the drawings.

In the drawings, 10 is the oven-casing of a burner of any well-known construction provided near its front end with a support 11, to 65 the upper end of which is pivoted at 12 a wheel 13, over which passes a rope, chain, belt, or other similar device 14, to the rear end of which is secured a weight 15, while its opposite end is secured to a bail 16, connected to a sliding door 17. The weight 15 practically balances the weight of the door 17, which is slidably mounted in the groove 18 in the casting 19, bolted to the flange 20 at the front end of the oven-casing 10. 70

The door 17 provides a ready means for charging the burner. At some convenient point in the length of the burner is a transverse member 21, extending across the bottom of the oven-casing 10, said transverse 80 member resting in a suitable groove in a rocker-plate 22, mounted upon the upper end of a suitable pier 23. The oven-casing 10 is adapted to rock on this plate 22 by means of the mechanism to be hereinafter described. 85

This rocking or tilting motion of the oven-casing causes first the front end thereof to assume a position below the horizontal plane and then by a reversal of the movement the front end is raised above the horizontal plane 90 and the rear end of the oven-casing is lowered beneath said plane. This tilting movement causes the oily substance which is contained in the sulfur and which separates therefrom during combustion to flow to the 95 lowest point of the oven-casing and leave the sulfur in the upper end free therefrom, so that the sulfur may be burned readily and the gas freed therefrom. These gases pass to the rear end of the oven and escape through the 100 outlet-pipe 24. This pipe is necessarily a fixed pipe, and it is obvious that to prevent the gas from escaping at the joint between the pipe and the movable rear end of the oven-casing 10 a hermetical seal must be 105 provided. This is accomplished by securing to the rear end of the oven-casing 10 a casting 25, surrounding the outlet-passage 26 of said oven-casing. This casting 25 is provided with an annular groove 27, which is 110 supplied with water from the pipe 28. To the lower end of the outlet-pipe 24 is secured

an annular flanged member 29, the flange of which extends into the water contained in the annular groove 27. It is obvious that by such a construction the oven-casing is free to rock in either direction without interfering with the fixed outlet-pipe 24, and a hermetical seal is provided, thereby preventing the gas which passes through the outlet 26 from escaping and obliging it to pass into the pipe 24.

While the transverse plate 21 is shown in the drawings as slightly back of the center of the oven-casing, so that the bulk of the weight of the casing is in front of the pier 23, it is obvious that the pier could be built further to the rear or the pier could be built well to the front of the oven and the automatic rocking device located at the rear of the oven without altering the principles of this invention. It is also obvious that the same results could be obtained if the oven-casing were rocked transversely rather than longitudinally, the main object of the invention being to free, by the tilting or rocking of the oven-casing, a portion of the sulfur contained therein from the oily substance removed therefrom in the process of combustion and alternately uncover a portion of the sulfur contained within the oven-casing in order to produce a complete combustion of all of the sulfur therein contained.

The pipe 28 connects with the main supply-pipe 30 and is provided with a valve 31, by which the amount of water flowing through said pipe into the annular groove 27 may be regulated. The free end of the burner-casing 10 rests upon a round roll, which rests on a piston-rod 32, mounted in a bearing 33 in the cylinder-head 34, while the piston 35 thereof is mounted to be freely revoluble in the cylinder 36. The cylinder 36 is mounted upon a suitable support 37, and normally the weight of the free end of the burner-casing retains the piston 35 in its extreme lowest position.

A pipe 38 communicates with the interior of the cylinder 36 below the lower face of the piston 35 when in its lower position, this pipe communicating with the main supply-pipe 30, and is provided with a hand-valve 39. The pipe 38 is also provided with a three-way valve 40, having an outlet connected to an exhaust-pipe 41. The plug 42 of said valve is provided with a forked arm 43, the forks of which straddle the stem 44 of a piston 45, mounted in a smaller cylinder 46, said stem being supported by means of the spider 47 and having upon its upper end a weight 48, which normally retains the piston 45 in its lowest position.

The stem 44 is provided with collars 49, 50, which in the longitudinal movement of said stem 44 contact with the arm 43 and operate the valve 40 to either admit water through the pipe 38 into the cylinder 36 or permit it

to exhaust therefrom through the outlet-pipe 41, as the case may be. A pipe 51 is provided with a hand-valve 52 and a three-way valve 53. The valve 53 is connected to an exhaust-pipe 54, and the plug of said valve is provided with a forked arm 55, which straddles a stem 56, secured to a laterally-extending plate 57, fastened to the burner-casing 10.

The stem 56 is provided with suitable collars 58, 58*, which act upon the arm 55 of the valve 53 to admit water to the cylinder 46 or exhaust it therefrom, as the case may be. The pipe 51, connecting with the pipe 38, connects with the cylinder 36. When the valve 39 is opened, permitting a flow of water from the main pipe 30 into the pipe 38, it is prevented from passing into the cylinder 36 by means of the valve 40, which is normally closed for admission; but it will pass through the pipe 51 of the secondary cylinder 46 and cause the piston 45 therein to be raised to its upper position. In doing this the collar 50 after it is moved upwardly for a short distance will contact with the forked arm 43 and move this to operate the valve 40 to shut off the exhaust 41 and open said valve to permit the flow of water in the pipe 38 to pass into the cylinder 36 to raise the front end of the oven-casing into the position shown in dotted lines. The piston 35 is moved upwardly until it reaches the cylinder-head, where its upward movement is stopped. It remains in this position until the pressure of the liquid beneath it is relieved by the opening of the exhaust.

As the front end of the burner moves upwardly the collar 58 on the stem 56, carried by said oven-casing, will come into contact with the arm 55 to operate the valve 53 to shut off further admission through the pipe 51 and open to the exhaust 54, thereby permitting the weight 48 to act upon the piston 45 to return it to its lower position, as shown in Fig. 2.

As the piston 45 descends the collar 49 will move for a slight distance and then come into contact with the forked arm 43 and operate the valve 40 to again shut off the admission to the cylinder 36 and open up the exhaust 41, thereby permitting the front end of the oven-casing by its weight to move the piston 35 downwardly to its normal position. This downward movement of the front end of the oven-casing will cause the collar 58 to move downwardly a slight distance and then come into contact with the arm 55 to again open the valve 53 to admit pressure beneath the piston 45 to repeat the operation. This lost motion between the collars 58 and 58* in operating upon the arm 55 and the lost motion between the collars 49, 50 in operating upon the arm 43 cause the oven-casing to remain at a standstill at each end of its tilting movement in either direction. This is an important feature of the invention, as

5 by this means the sulfur contained within the oven has all of the oily substance removed from its upper surface for a sufficient period of time to permit the process of combustion to proceed without the interference thereof.

Where two or more burners are used in conjunction, the main pipe 30 is continued beneath the additional oven-casings and is provided with branch pipes 60, in each of which is a hand-valve 61, by which any particular burner may be shut off when not desired for use. Each pipe 60 connects with the cylinder beneath its respective oven-casing, and each of these pipes 60 is provided with a three-way valve 62, having an arm 63 to operate it. This arm 63 is forked and straddles a stem 64, depending from a plate 65, secured to the under side of the first-mentioned 10 oven-casing 10. The stem 64 is provided with collars 66 67, which in the movement of the front end of the casing 10 contact with the arm 63 to open and close the valve 62 to permit each succeeding oven-casing to be 15 tilted by the admission and exhaust from its hydraulic cylinder, this admission and exhaust being regulated by means of the movement of the preceding oven-casing.

It is believed that the operation of the invention will be thoroughly understood from the foregoing without any further description.

Having thus described my invention, I claim—

35 1. In a sulfur-burner, the combination of an oven-casing; and hydraulic mechanism for tilting said casing.

2. In a sulfur-burner, the combination of an oven-casing; a support therefor; a rocking 40 connector between said support and casing; and hydraulic mechanism beneath said oven-casing for tilting it on said support.

3. In a sulfur-burner, the combination of an oven-casing; a support therefor at one 45 end of said casing; means interposed between said support and oven permitting the tilting of the latter; a second support for said casing at another point; and mechanism for automatically moving said second support 50 for effecting said tilting.

4. In a sulfur-burner, the combination of an oven-casing; a support therefor; means interposed between said support and oven 55 permitting the tilting of the latter; and hydraulic means for automatically effecting said tilting.

5. In a sulfur-burner, the combination of an oven-casing; a support therefor; means interposed between said support and oven 60 permitting the tilting of the latter; and means for automatically effecting said tilting and causing a halt in the movement of said oven in either direction before its return movement.

65 6. In a sulfur-burner, the combination of

an oven-casing; a support therefor; a rocking member interposed between said casing and said support; a cylinder; a piston therein supporting one end of said casing; and means for admitting motive force beneath said piston to raise that end of said casing.

7. In a sulfur-burner, the combination of an oven-casing; a support therefor; a rocking member interposed between said casing and said support; a cylinder; a piston therein supporting one end of said casing; a pipe communicating with said cylinder beneath said piston for the passage of motive force to and from said cylinder; and a three-way valve in said pipe to control the flow therethrough.

8. In a sulfur-burner, the combination of an oven-casing; a support therefor; a rocking member interposed between said casing and said support; a cylinder; a piston therein supporting one end of said casing; a pipe communicating with said cylinder beneath said piston for the passage of motive force to and from said cylinder; a three-way valve in said pipe to control the flow therethrough; and a device for automatically operating said valve.

9. In a sulfur-burner, the combination of an oven-casing; a support therefor; a rocking member interposed between said casing and said support; a cylinder; a piston therein supporting one end of said casing; a pipe communicating with said cylinder beneath said piston for the passage of motive force to and from said cylinder; a three-way valve in said pipe to control the flow therethrough; a second cylinder; and a piston therein adapted to operate said valve.

10. In a sulfur-burner, the combination of an oven-casing; a support therefor; a rocking member interposed between said casing and said support; a piston therein supporting one end of said casing; a pipe communicating with said cylinder beneath said piston for the passage of motive force to and from said cylinder; a three-way valve in said pipe to control the flow therethrough; a second cylinder; a piston therein adapted to operate said valve; and a weight upon said piston.

11. In a sulfur-burner, the combination of an oven-casing; a support therefor; a rocking member interposed between said casing and said support; a cylinder; a piston therein supporting one end of said casing; a pipe communicating with said cylinder beneath said piston for the passage of motive force to and from said cylinder; a three-way valve in said pipe to control the flow therethrough and provided with a radial arm; and a movable member provided with shoulders adapted to engage said arm to operate said valve.

12. In a sulfur-burner, the combination of an oven-casing; a support therefor; a rocking member interposed between said casing and said support; a cylinder; a piston therein

- supporting one end of said casing; a pipe communicating with said cylinder beneath said piston for the passage of motive force to and from said cylinder; a three-way valve in said pipe to control the flow therethrough and provided with a radial arm; and a movable member provided with adjustable shoulders adapted to engage said arm to operate said valve.
13. In a sulfur-burner, the combination of an oven-casing; a support therefor; a rocking member interposed between said casing and said support; a cylinder; a piston therein supporting one end of said casing; a pipe communicating with said cylinder beneath said piston for the passage of motive force to and from said cylinder; a three-way valve in said pipe to control the flow therethrough and provided with a radial arm; and a movable member provided with adjustable shoulders said shoulders being adapted to move some distance in either direction before engaging with said arm.
14. In a sulfur-burner, the combination of an oven-casing; a support therefor; a rocking member interposed between said casing and said support; a cylinder; a piston therein supporting one end of said casing; a pipe communicating with said cylinder beneath said piston for the passage of motive force to and from said cylinder; a three-way valve in said pipe to control the flow therethrough; a second cylinder; a piston therein adapted to operate said valve; a weight upon said piston; a pipe communicating with said second cylinder; a valve in said pipe; and a device for automatically operating said valve.
15. In a sulfur-burner, the combination of an oven-casing; a support therefor; a rocking member interposed between said casing and said support; a cylinder; a piston therein supporting one end of said casing; a pipe communicating with said cylinder beneath said piston for the passage of motive force to and from said cylinder; a three-way valve in said pipe to control the flow therethrough; a second cylinder; a piston therein adapted to operate said valve; a weight upon said piston; a pipe communicating with said second cylinder; a valve in said pipe; and a longitudinally-movable member provided with means for controlling the operation of said valve.
16. In a sulfur-burner, the combination of an oven-casing; a support therefor; a rocking member interposed between said casing and said support; a cylinder; a piston therein supporting one end of said casing; a pipe communicating with said cylinder beneath said piston for the passage of motive force to and from said cylinder; a three-way valve in said pipe to control the flow therethrough; a second cylinder; a piston therein adapted to operate said valve; a weight upon said piston; a pipe communicating with said second cylinder; a valve in said pipe; and an arm secured to said oven-casing provided with means for controlling the movement of said valve.
17. In a sulfur-burner, the combination of an oven-casing; a support therefor; a rocking member interposed between said casing and said support; a cylinder; a piston therein supporting one end of said casing; a pipe communicating with said cylinder beneath said piston for the passage of motive force to and from said cylinder; a three-way valve in said pipe to control the flow therethrough; a second cylinder; a piston therein adapted to operate said valve; a weight upon said piston; a pipe communicating with said second cylinder; a valve in said pipe; a depending stem secured to said oven-casing; an arm on said valve; and collars on said stem adapted to engage said arm and control its operation.
18. In a sulfur-burner, the combination of an oven-casing; a support therefor; a rocking member interposed between said casing and said support; a cylinder; a piston therein supporting one end of said casing; a pipe communicating with said cylinder beneath said piston for the passage of motive force to and from said cylinder; a three-way valve in said pipe to control the flow therethrough; a second cylinder; a piston therein adapted to operate said valve; a weight upon said piston; a pipe communicating with said second cylinder; a valve in said pipe; a depending stem secured to said oven-casing; an arm on said valve; and adjustable collars on said stem adapted to engage said arm and control its operation.
19. In a sulfur-burner, the combination of an oven-casing provided with an outlet-passage; an outlet-pipe; and an annular water seal between said pipe and casing and surrounding the former.
20. In a sulfur-burner, the combination of an oven-casing adapted to rock and provided with an outlet-passage at a moving point; a fixed outlet-pipe; and a water seal between said pipe and casing.
21. In a sulfur-burner, the combination of an oven-casing adapted to rock and provided with an outlet-passage at a moving point; a fixed outlet-pipe; and a flexible connection between said pipe and casing.
22. In a sulfur-burner, the combination of an oven-casing adapted to rock and provided with an outlet-passage at a moving point; a fixed outlet-pipe; and an annular ring surrounding said passage provided with a groove adapted to receive the lower end of said pipe and to hold a liquid adapted to seal the joint.
23. In a sulfur-burner, the combination of an oven-casing adapted to rock and provided with an outlet-passage at a moving point; a fixed outlet-pipe; an annular ring surrounding said passage provided with a groove adapted to receive the lower end of said pipe; and means for supplying liquid to said groove.

24. In a sulfur-burner, the combination of two oven-casings; means for tilting one of said casings; and means operated by the movement of the first casing for tilting the second casing.

25. In a sulfur-burner, the combination of two oven-casings; means for tilting one of said casings; a hydraulic cylinder for tilting the other; a valve for controlling the operation of said hydraulic cylinder; and an arm

secured to the first casing adapted to operate said valve.

Signed by me at Groveton, Northumberland, New Hampshire, this 20th day of October, 1906.

CHARLES E. SAVAGE.
